CLAIM

The ornamental design for a vibrating handle for tooth-cleaner, as shown and described.

DESCRIPTION

FIG. 1 is a perspective view of the vibrating handle for toothcleaner;

FIG. 2 is a top view of the vibrating handle;

FIG. 3 is a back view of the vibrating handle;

FIG. 4 is a front view of the vibrating handle;

FIG. 5 is a side view of the vibrating handle, the opposite side being a mirror image; and,

FIG. 6 is a bottom view of the vibrating handle.

The broken lines are for illustrative purposes only and form no part of the claimed design.
